EXPANSIBLE BOOK RACK

Herbert C. Sexton, Los Angeles, Calif.

Application March 1, 1955, Serial No. 34,806

Term of patent 14 years

(Cl. D33—3)

FIG. 1

FIG. 2

FIG. 3

Fig. 1 is a side elevation of an expandable book rack embodying my new design;

Fig. 2 is a front elevation thereof on a slightly enlarged scale; and

Fig. 3 is a perspective view on a smaller scale illustrating the rack in an expanded position.

I claim:

The ornamental design for an expandable book rack.
